Filed Feb. 20, 1967, Ser. No. 5,885

Term of patent 14 years

(Cl. D16—2)

FIG. 2

FIG. 3

FIG. 1

FIG. 1 is a perspective view of a meter for electrochemical analysis, showing our new design and particularly the front, top and one side thereof;

FIG. 2 is a front view of the meter shown in FIG. 1; and

FIG. 3 is a side view of the meter shown in FIG. 1. The rear view of the meter is substantially plain and unadorned.

The dominant features of our design reside in the portions shown in full lines.

We claim:

The ornamental design for a meter for electrochemical analysis, substantially as shown and described.
